UNITED STATES PATENT OFFICE.

MICHAEL B. RYAN, OF BOSTON, MASSACHUSETTS.

BED-SPRING FABRIC.

1,186,843.

Specification of Letters Patent. Patented June 13, 1916.

Application filed October 14, 1907. Serial No. 397,384.

To all whom it may concern:

Be it known that I, MICHAEL B. RYAN, a citizen of the United States, residing at Boston, in the county of Suffolk and State 5 of Massachusetts, have invented new and useful Improvements in Bed-Spring Fabrics, of which the following is a specification.

The object of this invention is to provide a bed spring which shall be strong, light, 10 cheap and durable and which is so constructed that the parts are capable of being manufactured and assembled in an electric welding machine, so that when the spring is completed the different links composing the 15 same are welded at their ends, forming a very strong and light construction, with completely closed eyes.

It is further the object of this invention to so construct and assemble the links forming 20 the bed spring that the main body portion of each link shall lie in and form the upper surface of said bed spring and present to the mattress which is placed thereon an even and smooth surface with all the parts which 25 project from said surface projecting downwardly therebelow, so that the mattress may be pulled across the upper surface of the spring with ease without tearing or wearing said mattress.

30 The invention consists in the combination and arrangement of parts set forth in the following specification and particularly pointed out in the claims thereof.

Referring to the drawings: Figure 1 is a 35 plan view of a portion of my improved bed spring. Fig. 2 is an end elevation of the same. Fig. 3 is a side elevation of the same.

Like numerals refer to like parts throughout the several views of the drawings.

40 In the drawings, 5, 5 are links forming a portion of a series of links extending longitudinally of the spring. 6, 6 are links forming a portion of a series extending laterally of the spring. All of the links are formed 45 of wire and the entire spring is formed of a plurality of series of links 5 joined together and extending longitudinally of the spring and a plurality of series of links 6 joined together and to said longitudinal series and 50 extending laterally of the spring.

The links 6 each consists of a body portion 7 and two end portions 8, 8 terminating at 9, 9. The end portions 8 are each bent downwardly to form an eye 10 and the termination 9 of the end portion 8 is welded to 55 the under side of the body portion 7 at each

end of the link 6. The eyes 10, 10 lie in a vertical plane.

The link 5 is formed of wire and consists of a body portion 11, the opposite ends of 60 said link terminating in eyes 12 and 13. The eye 12 is formed by bending the end portion 14 of the wire downwardly, with its termination 15 welded to the under side of the body portion 11, thus forming an eye 65 which lies in a vertical plane. The other eye 13 is formed by bending the end portion 16 of the wire forming the link downwardly and laterally to form a horizontal eye, the termination 17 of the end 16 being prefer- 70 ably welded to the under side of the body portion 11. It will be noted by reference to Fig. 3 that the top or upper surface of the horizontal eye 13 lies in the same plane as the bottom or under surface of the body portion 11 of the link 5. The links 5, 5, as particularly shown in plan view, are joined together and the links 6, 6 are joined to the horizontal eyes 13 of the links 5, 5. It will thus be seen that the links 5, 5 are joined 75 directly together, while the links 6, 6 are joined together to form a series by means of the horizontal eyes 13 of the links 5.

It will be noted that the body portions 11, 11 and 7, 7 of the links 5 and 6, respectively, 80 lie substantially in the same plane, so that said body portions constitute the upper surface of the bed spring, and that all the terminating ends of the wires which form the links, both 5, 5 and 6, 6, project below the 85 body portions, so that said spring presents only the rounded wire body portion as an upper surface thereof and a mattress when placed thereon or when dragged thereover will not be worn or torn thereby.

90 The spring, as a whole, can be assembled and welded upon an electric welding machine which is to form the subject matter of a separate application for Letters Patent by applicant.

95 While I prefer to weld the terminating ends of the links to the body portions thereof, as hereinbefore described, on account of the great strength and durability it imparts to the spring, it is evident that without departing from the spirit of my invention the links 5, 5 and 6, 6 may be formed as hereinbefore described without welding the terminating ends of the wires to the body portions thereof. The welding of the ends of 100 the links to the body portion thereof to form the links, in addition to making a

smooth and light construction, prevents the eye from opening under tension caused by the weight upon the spring and, therefore, prevents the spring from sagging after having been used for a time. This construction, therefore, adds to the durability and resiliency of the spring as a whole.

It will be seen that by welding the terminations of the end portions of the different links to the body portions thereof, great strength is given to the eye portion of the link as compared with a link in which the eyes are made by simply bending the same but in which the termination of the end of the wire is not soldered to the body portion, so that links made in accordance with my invention, as hereinbefore described, and welded, enable a very much lighter and very much smaller gage wire to be used than where the ends of the links are not soldered or welded to the body portion, thus reducing the weight and expense of the spring.

Having thus described my invention, what I claim and desire by Letters Patent to secure is:

1. In a bed spring fabric, a plurality of longitudinal members, each of said longitudinal members comprising a plurality of successive links connected directly to each other, each of said successive links consisting of a piece of wire, each of the end portions of said wire being bent to form an eye, each of said end portions at its termination being welded to the body portion of said wire, whereby said eyes are completely closed, and a plurality of lateral links connecting links of adjacent longitudinal members together, two of said lateral links connected to one eye of one of said longitudinal links extending therefrom in opposite directions and connected at their opposite ends to one eye of one of each of the laterally adjacent longitudinal links.

2. In a bed spring fabric, a plurality of longitudinal members, each of said longitudinal members comprising a plurality of successive links, each of said successive links consisting of a piece of wire having a straight body portion in alinement with the body portions of the others of said successive links, each of said end portions being bent to form an eye, said eyes being interlocked with the eyes of the links adjacent thereto, and a plurality of lateral links connecting the adjacent longitudinal members together, each of said lateral links terminating at its opposite ends, respectively, in an eye, said eyes interlocked with the eyes of two laterally adjacent longitudinal links.

3. In a bed spring fabric, a plurality of longitudinal members, each of said longitudinal members comprising a plurality of successive links connected directly to each other, said successive links being duplicates of each other, each of said links consisting of

a piece of wire having a straight body portion in alinement with the body portions of the others of said successive links, each of the end portions of said wire being bent to form an eye, and a plurality of lateral links connecting adjacent longitudinal members together, each of said lateral links terminating at its opposite ends, respectively, in an eye, said eyes interlocked with the eyes of two laterally adjacent longitudinal links.

4. In a bed spring fabric, a plurality of longitudinal members, each of said longitudinal members comprising a plurality of successive links connected directly to each other, each of said successive links consisting of a piece of wire, one end of which is bent to form a horizontal eye and the other end of which is bent to form a vertical eye, the vertical and horizontal eyes of each of said links being interlocked with the horizontal and vertical eyes, respectively, of the links in said longitudinal member adjacent thereto, and a plurality of lateral links connecting adjacent longitudinal members together, each of said lateral links terminating at its opposite ends, respectively, in an eye, said eyes interlocked with eyes of two laterally adjacent longitudinal links.

5. In a bed spring fabric, a plurality of longitudinal members, each of said longitudinal members comprising a plurality of successive links connected directly to each other, said successive links being duplicates of each other, each of said links consisting of a piece of wire having a straight body portion in alinement with the body portions of the others of said successive links, the opposite ends of each of said wires being bent to form vertical and horizontal eyes, respectively, and a plurality of lateral links connecting adjacent longitudinal members together, each of said lateral links terminating at its opposite ends, respectively, in an eye, said eyes interlocked with eyes of two laterally adjacent longitudinal links.

6. A bed spring fabric consisting of a plurality of series of links joined together and extending longitudinally of said bed spring, each link of said series consisting of a piece of wire, one end portion of said wire being bent laterally and offset downwardly thereof to form a horizontal eye, the top of said eye and the bottom of the body portion of said link lying in substantially the same plane, and the other end bent downwardly in a vertical plane to form an eye below said plane of said body portion, and a plurality of series of links extending laterally of said spring joined directly to the horizontal eyes of said longitudinal links, each of said lateral links consisting of a piece of wire, each of the opposite end portions of said wire being bent downwardly to form an eye below the body portion of said links.

7. A bed spring fabric consisting of a plu-

rality of series of links joined together and extending longitudinally thereof, each link consisting of a piece of wire, one end portion of said wire being bent downwardly and laterally thereof to form an eye, said end portion at its termination being welded to the under side of said body portion, and a plurality of series of links extending laterally, said last-mentioned links being joined 10 to said longitudinally disposed links, each of said lateral links consisting of a piece of wire, each of the opposite end portions of said wire being bent to form an eye, each of said end portions at its termination being welded to the under side of the body portion of said wire.

8. A link fabric, comprising a plurality of longitudinally arranged members, one end

of each member being provided with a vertical loop arranged with the loop entirely on one side of the member, and a horizontally extending loop formed at the opposite end of said member and connected to the vertical loop of the succeeding member, and transverse links formed with vertical loops linked 20 through said horizontal loops, the loops of the transverse links extending below the general horizontal plane of the fabric.

In testimony whereof I have hereunto set my hand in presence of two subscribing witnesses.

MICHAEL B. RYAN.
